UNITED STATES PATENT OFFICE.

JAMES G. CROUCHER, OF SASKATOON, SASKATCHEWAN, CANADA.

GAS-GENERATOR.

1,258,877.

Specification of Letters Patent. Patented Mar. 12, 1918.

Application filed July 26, 1916. Serial No. 111,427.

To all whom it may concern:

Be it known that I, JAMES G. CROUCHER, a citizen of the United States, residing at 5 Saskatoon, in the Province of Saskatchewan, Dominion of Canada, have invented a new and useful Improvement in Gas-Generators, of which the following is a specification.

This invention relates to new and useful 10 acetylene generators, wherein the structure is extremely simple, safe and effective in operation, and in which the gas producing agent such as calcium carbid is fed automatically in small and sufficient quantities 15 into a body of water to liberate and maintain gas under a constant, even and low pressure, thus avoiding fluctuation of light emitted by the burners. Another object is to provide means wherein the danger of explosion caused by a flash back is reduced 20 to a minimum. A further and important object is to prevent water in the generator tank from freezing. Other and further objects and advantages of the invention will 25 be hereinafter set forth, and the novel features thereof defined in the appended claims.

In the accompanying drawings forming 30 part of this specification, Figure 1 is a sectional elevation of my invention; Fig. 2 is a section of a detail taken upon the line X—X of Fig. 1, and Fig. 3 is an edge view of the carbid feeding wheels.

Like numerals of reference refer to like 35 parts in the several figures of the drawings.

Referring to the drawings, A represents 40 a low pressure tank of any suitable configuration having a cover B suitably secured thereon. The walls of this tank and cover are constructed with a plurality of spaced 45 thicknesses of material 2 forming dead air cells 3 and spaces 4 which are packed with poor heat conducting material or the very best frost resisting material 5 serving to protect the entire generator from the effects 50 of cold. This is important in a cold climate because it is hazardous if the liquid in the generator freezes. The inner chamber C is cylindrical and forms a tank to contain 55 water. In the lower portion of this tank a rotatable paddle 6 is journaled. This paddle can be turned by a crank 7 projecting through the wall of the structure to stir the residue and assist in cleaning the tank. 60 The tank is filled with water through a funnel 8 and a pipe 9 leading downwardly and 65 upwardly into the lower portion of the chamber, the inner end of said pipe being opened and closed by a valve 10 having a stem 11 projecting outwardly through the 70 wall of the structure and turned by the handle 12. In use the chamber is filled to approximately the level of the funnel 8 and replenished from time to time to suit requirements. A valved outlet 10' provides 75 means for draining the tank of water and sediment.

Located above the level of the water in the tank is a cylindrical shell 13, the lower end of which is turned inwardly and secured 80 to the inner surface of the wall of the chamber. This shell is spaced inwardly from the inner wall of the chamber C, said space forming a sealing well and being filled or nearly filled with a sealing liquid such as 85 coal oil or any non-freezing liquid. Placed in the upper end of the cylindrical shell is a carbid hopper 14, which tapers downwardly and inwardly, the upper end of said hopper being closed by a cover 14' and 90 formed with a heavy flange 15 which reaches over and rests on the top of the shell 13, thus supporting the hopper and leaving the reservoir free to be lifted out of the shell. This hopper is formed with an outlet 16 in 95 its lower end in which the peripheries of a pair of carbid feeding wheels 17 and 18 above the water in the tank revolve, said feeding wheels being mounted upon a shaft 19, which is freely journaled in a pair of 100 depending brackets 20 and 21 secured to the lower end of the hopper. The lower end of the shell 13 which forms the sealing reservoir is supported by brackets 22 projecting inwardly from the wall of chamber C. D 105 represents a dome or what I term a "gasometer," said dome being in the form of an inverted cup having its cylindrical side wall 23 dipping down into the body of oil in the sealing reservoir. The lower edge of the 110 wall 23 is formed with an outturned flange 24 above which are secured a plurality of circular weights 25, which tend to hold the dome down under the influence of upward pressure to an even and low pressure of gas 115 exerted within the dome.

Extending upwardly between the feed 120 wheels 17 and 18 is a feed operating rod 26, the lower portion of which is pivotally secured to the arm 27 of a bell crank, said 125 bell crank being freely journaled at its angle upon the shaft 19. The upper end

of this rod slides freely through a sleeve 28, which is supported laterally by a bracket 29 secured in the hopper and through an opening 28' in the cover 14'. The lower 5 end of the sleeve 28 is formed with an outwardly and downwardly flaring guard 30, which is secured to supports 31 extending inwardly from the wall of the hopper. This 10 guard holds the carbid in the hopper from pressing against the rod 26, and assists in producing very even flow of carbid to the feed wheels. Placed around the feed rod 15 is a coil expansion spring 32, one end of which bears downwardly against an inwardly projecting shoulder 33 at the lower end of the sleeve 28. The upper end of said 20 rod presses against a collar 34 secured to the feed rod and guided in its up and down movement by the sleeve. This spring tends to force the rod upwardly and returns the bell crank to normal position as shown in Fig. 1. Mounted upon one of the feed 25 wheels 17 adjacent the bell crank is a ratchet wheel 35 with the teeth of which a weighted pawl 36 mounted upon the arm 37 of the bell crank engages automatically to cause the feed wheels 17 and 18 to revolve a step at a time when the dome presses the rod 26 down. When the feed rod 26 is released by 30 the raising of the dome, the spring 33 forces the feed rod up and causes the pawl to sweep over the teeth of the ratchet wheels in readiness to repeat this operation.

The peripheries of the feed wheels are 35 formed with pockets 38, which receive the carbid material from the hopper and the center of the feed wheels is arranged at one side of the center of the outlet of the hopper so that the weight of the carbid received in 40 the pockets will assist in causing the wheels to revolve. The lower end of the feed rod 26 is formed with a brake shoe 39, which bears upon the peripheries of the feed 45 wheels to check the revolution thereof when the feed rod has returned into superior position. This brake positively stops the feeding of carbid and prevents an excessive amount of the gas generated. The upper end of the feed rod is formed with a stop 50 or buffer 40 against which the shank of an adjusting bolt 41 presses when the dome lowers, due to decrease of the volume of gas. The pockets 38 in the wheels 17 and 55 18 are arranged in a zig zag course, so that with a slight turn of the shaft 19, one or the other feed wheel will immediately drop some carbid into the water making almost a continuous run of carbid to the water, while the wheels are in motion. By this arrangement also only a very small amount of carbid is dropped into the water at a time, but this small amount is sufficient to generate gas and produce a very even pressure.

The side wall of the tank has guides 43 60 over which lugs such as 44 on the dome slide

freely up and down to prevent the dome from turning. The hopper is filled or replenished with calcium carbid from time to time by opening the cover B and removing a screw plug 45 from the top of the dome. 70 The spout of a funnel is next inserted through the opening left by said plug and a corresponding opening 46 in the cover 14' and the carbid fed through the funnel. The use of coal oil as a sealing medium in the 75 sealing reservoir is for frost protection. The depth of this oil depends upon the capacity of the generator. If an excessive amount of gas occurs in the generator, it will raise the gasometer and the gas will 80 bubble through the sealing medium and into that portion of the chamber above the dome, from whence it will egress from the generator through a relief safety pipe 47 to the outer atmosphere. Gas is conducted from 85 the generator for commercial use through a filter 50, the upper end of which is provided with a pipe 51 extending upwardly through a duct 52 passing through the hopper and its cover and into the space below the dome. 90 The lower end of the filter has a duct 53 leading outwardly through the wall of the generator and valved at its outer end. A drip pocket in the pipe 53 in the shape of a closed pipe 54 extends downwardly into the water in the tank for any condensation 95 which may occur from the use of the filter or in the pipes leading from the generator.

In accordance with the patent statutes I have described the principles of operation 100 of my invention, together with the apparatus which I now consider to represent the best embodiment thereof, but I desire to have it understood that the construction shown is only illustrative, and that the invention can be carried out by other means 105 and applied to uses other than those above set forth within the scope of the following claims.

Having described my invention what I 110 claim as new and desire to protect by Letters Patent is:—

1. A gas generator, comprising, in combination, a tank having a body of water therein, a sealing liquid receptacle encompassing 115 said tank on its inner wall, a freely movable carbid hopper removably mounted upon said receptacle and having an outlet above said water, a freely movable dome enveloping said hopper and arranged with its wall dipping into the sealing liquid in said receptacle, a revoluble carbid feed wheel having pockets in its periphery arranged to receive carbid from said outlet in said hopper and drop the same in said water, a pawl and 120 ratchet arranged to impart a step by step revolving movement to said wheel, a feed rod connected with said pawl and arranged to step the same by the lowering of said dome, a spring arranged to return said pawl 125

into normal position when said dome returns into superior position, a brake carried by said rod arranged to engage and hold said wheel from revolving when said dome 5 assumes superior position, a gas supply duct connected with the space below said dome and an escape duct connected with the space above said dome.

2. A gas generator, comprising, in combination, a tank having a body of water therein, a sealing liquid receptacle encompassing said tank on its inner wall, a freely movable carbide hopper removably mounted upon said receptacle and having an outlet 10 above said water, a freely movable dome enveloping said hopper and arranged with its wall dipping into the sealing liquid in said receptacle, revolute carbide feed wheels having pockets in staggered arrangement 15 in their peripheries arranged to receive carbide from said outlet in said hopper and drop the same in said water, a pawl and ratchet arranged to impart a step by step revolving movement to said wheels, a feed rod connected with said pawl and arranged to step the same by the lowering of said dome, a spring arranged to return said pawl into normal position when said dome returns into superior position, a brake carried by 20 said rod arranged to engage and hold said wheels from revolving when said dome assumes superior position, a gas supply duct connected with the space below said dome and an escape duct connected with the space 25 above said dome.

3. A gas generator, comprising, in combination, a tank having a body of water therein, a freely movable carbide hopper in said tank above the level of water therein 30 having an outlet in its lower end, a sealing liquid receptacle surrounding said hopper, a freely movable dome enveloping said hopper and arranged with its wall dipping into 35

the sealing liquid in said receptacle, a pair of revolute carbide feed wheels journaled 45 below said hopper and having pockets in their peripheries arranged in said outlet to receive and drop carbide into the water in said tank, said pockets being arranged in staggered form, ratchet means operated by 50 the lowering of said dome for revolving said wheels and returnable to normal position after each feeding operation, a feed rod carried by said ratchet means and arranged to step the same by the lowering of said 55 dome, a brake on said feed rod for holding the feeding wheels stationary after said dome rises into superior position, and a service gas duct leading from the space below said dome and above said hopper to 60 the exterior of said generator.

4. A gas generator, comprising, in combination, a tank having a body of water therein and formed with insulated walls, a liquid sealing chamber circulating around 65 the inner surface of the side of said tank above said water, a freely movable dome having its side dipping into the liquid seal, a freely movable carbide hopper supported in said sealing chamber having a lower outlet, a rotatable member for receiving carbide from said hopper and adapted when rotated to deliver a portion of its load into said water for the generation of gas, ratchet means for revolving said rotatable member 70 by the lowering of said dome, a feed rod on said ratchet means arranged to step the same by the lowering of said dome and having a brake adapted to prevent the rotation of the ratchet means by the raising of said dome, 75 and a service duct leading from the space above said water and below said dome.

In testimony whereof, I have signed my name to this specification.

JAMES G. CROUCHER.
